FRICITION TYPE BOTTLE CAP REMOVER

James E. Guthrie, 5917-B Woodson Road,
Kansas City, Mo. 64133

Filed Sept. 2, 1969, Ser. No. 18,943

Term of patent 14 years

Int. Cl. D8—02

U.S. Cl. D8—18

Fig.1.

Fig.6.

Fig.5.

Fig.3.

Fig.2.

Fig.4.

FIG. 1 is a perspective view of a friction type bottle cap remover showing my new design;

FIG. 2 is a rear elevational view;

FIG. 3 is a top plan view;

FIG. 4 is a bottom plan view;

FIG. 5 is an elevational view from the right of FIG. 2; and

FIG. 6 is an elevational view from the left of FIG. 2.

I claim:

The ornamental design for a friction type bottle cap remover, as shown.
